UNITED STATES PATENT OFFICE.

WILLIAM THOMAS BUCKINGHAM ROBERTS, OF LEICESTER, ENGLAND, ASSIGNOR TO UNITED SHOE MACHINERY CORPORATION, OF PATERSON, NEW JERSEY, A CORPORATION OF NEW JERSEY.

MACHINE FOR WORKING UPPERS OVER LASTS.

Application filed October 15, 1921. Serial No. 507,900.

To all whom it may concern:

Be it known that I, WILLIAM THOMAS BUCKINGHAM ROBERTS, a subject of the King of England, residing at Leicester, Leicestershire, England, have invented certain Improvements in Machines for Working Uppers over Lasts, of which the following description, in connection with the accompanying drawings, is a specification, like reference characters on the drawings indicating like parts in the several figures.

This invention relates to machines for working uppers over lasts, and is herein illustrated in its application to a machine including in its organization means for pulling the upper over the last and means for lasting the toe of the shoe. It will be recognized, however, that in many of its features the invention is not limited to machines having both pulling-over means and lasting means.

A feature of the invention consists in a novel organization comprising upper pulling means whereby different portions of the upper are pulled at different times, the machine herein shown being organized to defer the pulling of the upper at the toe until after it has been pulled at the sides of the forepart and opportunity has been afforded for adjusting the laterally tensioned upper on the last, for example to straighten the tip seam. In the illustrative machine the margin of the upper is left free about the toe during the updraw movement of the side grippers, which may have also a foredrawing movement as in prior machines, and is gripped and pulled at the end of the toe at a later stage of the cycle following a subsequent actuation of the starting means. An important advantage in such a sequence of operations is that it facilitates the adjustment of the upper by the movement of the side grippers lengthwise of the last and avoids danger of wrinkling the upper between the side grippers and the means which grips or clamps the upper about the toe. In the machine illustrated the pulling of the upper at the toe is effected by clamping means which engages the upper continuously round the toe from one side of the toe to the other, the machine including in its organization also means for subsequently lasting the toe of the shoe.

A further feature of the invention con-

sists in a novel pulling-over organization in which the pulling of the upper at the toe is effected by the aid of toe embracing wipers upon which the upper is clamped. In the construction shown the wipers are advanced and closed yielding about the toe as the upper is pulled at the sides of the forepart, preparatory to the clamping of the upper on the wipers and the pulling of the upper at the toe in a later stage of the cycle, the machine having also means for operating the wipers subsequently to wipe the upper inwardly over the bottom of the last.

The invention also provides a novel organization of pulling-over and lasting means including among its novel features provision for wiping the toe of the upper automatically heightwise of the last, i. e., for "upwiping" the upper, by the operation of wipers which are closed into embracing relation to the toe, and provision for controlling the margin of the upper during the upper pulling operation and the overwiping operation of the wipers by clamping pressure which, in the construction shown, is relaxed to facilitate the overwiping of the upper by the advancing and closing of the wipers. Features are also to be recognized in novel wiper operating means, the construction shown comprising means for advancing and closing the wipers first yieldingly and then positively together with means for varying the extent of the final positive movement of the wipers.

In another important aspect the invention relates to the fastening of the upper in lasted position, the machine illustrated having a novel organization of means for applying and fastening a binder to the shoe and for feeding binder material. Among the features included in this part of the invention are novel tacker mechanism and novel means for fastening the ends of a binder to anchor tacks, the construction shown comprising devices which move with the wipers and are operative in a novel manner to drive anchor tacks at the sides of the toe and to twist the ends of a binder about the tacks. Important features are also to be recognized in novel means for feeding binder material and in novel means for determining the length of the binder, the machine illustrated having means for

determining the length of the feed of the binder material automatically in accordance with the size of the shoe. In the construction shown the binder wire is fed automatically into a groove in the wipers and the proper length of wire is cut off at the end of the cycle of operations on a shoe for use in lasting the next shoe, the length of the feed being determined automatically by 10 the size of the wipers with which the machine is equipped.

The above and other features of the invention, including certain details of construction and combinations of parts, will 15 now be described with reference to the accompanying drawings and pointed out in the claims.

In the drawings,

Fig. 1 shows in side elevation the head 20 portion of a machine in which the invention is embodied, with the mechanism for feeding the toe binder wire removed for the sake of clearness in the illustration,

Fig. 2 is a sectional side elevation of the 25 toe wiper mechanism, with the tack driving and binder fastening devices omitted for the sake of clearness,

Fig. 3 is a plan view of the mechanism shown in Fig. 2, with parts broken away, 30 the position of the tack driving and binder fastening devices being indicated diagrammatically,

Fig. 4 is an elevation, partly in section, 35 of one of the tack driving and binder fastening devices,

Fig. 5 is a plan view of the parts shown in Fig. 4,

Fig. 6 is an enlarged vertical section 40 showing the pair of tack fingers of the mechanism illustrated in Fig. 4,

Fig. 7 is a side elevation of the tack fingers shown in Fig. 6,

Fig. 8 is an inverted plan view of the 45 tack fingers shown in Fig. 6,

Fig. 9 is a side elevation, partly in section, 50 of the upper clamping and last depressing devices,

Fig. 10 is an inverted plan view of the 55 clamping and depressing feet shown in Fig. 9,

Fig. 11 is an elevation, partly in section, 60 of the binder wire feeding and severing mechanism which is omitted from Fig. 1, together with a portion of the frame on which this mechanism is mounted,

Fig. 12 is a plan view of the parts shown in Fig. 11, and

Fig. 13 is an end elevation of the parts 65 shown in Fig. 11, with a portion of the structure broken away.

For purposes of illustration the invention is herein shown in its application to a well-known type of pulling-over machine 70 characteristic features of which are shown 75 and described in detail in various prior

United States Letters Patent, including Patent No. 1,029,387, granted on June 11, 1912, upon an application of R. F. McFeely, to which reference may be made for a better understanding of details of the organization of the machine not hereinafter particularly described. As in one of the customary forms of this type of machine, the machine herein shown is provided (Fig. 1) with a single pair of side grippers 1 for

each side of the forepart of the shoe, which are operated from the usual cam shaft through updraw levers 3 to pull the upper yieldingly and hold it under tension, and with means including opposite side

driver bars 7 for driving at each side of the forepart a pair of upper fastening tacks at the rear of the tacks hereinafter referred to for fastening the toe binder wire.

In the present machine however the usual toe gripper and the front arm with its upper fastening mechanism are omitted to make way for the novel mechanism of the present invention whereby the upper is

pulled over the toe and wiped inwardly and fastened in lasted position. Corresponding portions of the frame of prior machines are also omitted, and in place thereof the present machine has a frame casting 2 which extends forwardly and centrally of the machine and substantially parallel to the plane of the bottom of the shoe,

this casting having bores extending therethrough from top to bottom to receive the upper clamping and last depressing members, as illustrated in Fig. 9 and as more particularly hereinafter described. On a forward extension of the frame casting 2

is a guide 4 for a wiper head 5 which is mounted to slide lengthwise of the shoe toward and from the toe of the shoe. To assist in holding the casting 2 firmly in place

a stay member 6 is provided which is secured at one end to said casting and at its other end to the main frame of the

machine.

The wiper head 5 (Figs. 1 and 2) extends downwardly from its guide and has upper and lower plates in planes parallel to the guide and between which are mounted

for arcuate swinging movement members which carry the wipers and their associated tack driving and binder fastening devices, hereinafter frequently termed for convenience "tackers", these members being arranged to swing about a common center at a point substantially coincident with the inner corners of the operative edges of the wipers. Projecting through

arcuate slots 8 (Fig. 3) located respectively at the opposite extremities of the upper plate 10 of the wiper head are studs 12 through which power is applied to operate the wipers. Each stud projects outwardly from an arcuate plate 14 guided

115

120

125

130

135

between the upper and lower plates of the head and having projecting from its lower face a stud 16 on which is a freely rotatable pinion 18 meshing with an internal arcuate rack on a member 20 which spaces the upper and lower plates of the head and with an external arcuate rack on a carrier 22 for the corresponding wiper and tacker, this carrier also being guided between the plates for arcuate movement. The carriers 22 have mounted on their lower faces wipers 24 which project beyond them toward the shoe a sufficient distance to provide an upper flat surface upon which the upper materials round the toe end may be clamped outspread as hereinafter described. Each carrier 22 has also a rectilinear guideway 26 extending parallel to the shoe bottom and in the general direction of that end portion of the operative wiper edge which engages the side of the toe.

Each of the two studs 12 projecting through the upper plate 10 is connected to a link 28 which is guided on a flat surface 30 parallel to the wiper head guide and is pivoted to an end of a curved lever 32 the fulcrum of which, midway between its ends, is formed by a stud 34 projecting from the lower face of a bar 36, the upper face of this bar being formed as a rack. The rack bar 36 is guided in the wiper head for movement lengthwise of the shoe, and carries a spring pressed plunger 38 with a sharpened end seated in a wide V-notch 40 in the curved lever 32 to maintain the lever normally in a centralized position while permitting the wipers to swing as required to adjust themselves to toes of different shapes.

The tack driving mechanisms (Figs. 4 to 8) for driving at the opposite sides of the toe the tacks to which the ends of the binder are fastened are carried in tubular casings 42 which are arranged to move into and out of operative position with the wipers. Each casing has near its lower end a projecting flanged portion 44 constructed to slide into the rectilinear guideway 26 in the wiper carrier 22. Below the projecting portion 44 the tubular casing 42 has formed on it a boss 46 which receives a screw 48 passing through the wiper 24 and by which the casing is fastened to the wiper. Extending from the casing over the wiper is an arm 50 the end of which is confined between the upper face of the wiper carrier 22 and the lower face of the plate 10 to assist in steadyng the tacker mechanism. The casing 42 extends upward approximately at right angles to the plane of the wipers and is formed to receive a tack driver guide 52. This guide is cylindrical and is itself bored axially to receive a driver 54 and a driver bar 56. On the lower end of the guide are pivotally mounted a pair of oppositely disposed tack holding fingers 58 which are pressed yieldingly toward each other by a spring 60. The lower ends of the two tack fingers, when the fingers are pressed together, form a hemisphere, and one of the fingers has near its lower end, transverse to the driver passage and parallel to the meeting faces of the fingers, a passage 62 through which the binder wire is fed, as will be hereinafter described. Each of these passages, at that end remote from the adjacent end of the binder wire, is flared, the flare extending approximately to the edge of the tack at the junction of the fingers at the lowest point of the hemisphere.

The upper portion of the guide 52 is threaded, and the threads mesh with the threads of a screw 64 so that if the guide is rotated it will move lengthwise of the bore in the casing. The screw 64 extends into an unthreaded hole in the casing 42 which is parallel to the axis of the guide and opens into the bore of the guide, and is locked in position by a set screw 66. By adjustment of the screw 64 upwardly or downwardly the position of the guide may be varied in order to locate the passage 62 in the correct position to receive the binder wire.

For rotating the guide 52 to twist the end of the wire about the tack, the guide has formed upon it a peripheral series of gear teeth which mesh with a gear 68 fast on the lower end of a shaft 70 rotatably mounted in a projecting portion of the casing 42 in parallel relation to the guide 52. Each shaft 70 is driven by means of a flexible shaft 72 at the time when the upper has been wiped over the edge of the last bottom and the tacks have been driven, the guide thus being turned and at the same time elevated by its threaded connection with the screw 64 to twist the end of the wire about the partially driven tack and to raise the tack fingers finally above the head of the tack and to free them from the wire which slips through the passage 62 as the fingers are rotated and raised.

The driver bar guide 52 has at its lower end a relatively small bore 74 in which the driver 54 is guided, and at a short distance from the lower end of the guide this bore is enlarged to receive the driver bar 56 and a lifting spring 76 which bears upwardly against a shoulder on the lower end of the bar 56. The upper end portion of the driver 54 is received in a bore in the bar 56 and is seated against a screw plug 78, the driver being secured in place by means of clamping screws 80. On the upper end of the bar 56 is adjustably threaded a cap 81. The tack is discharged into the tack pocket formed by the fingers 58 from a duct 82 formed in the guide 52 and the casing 42, the tacks being fed through a flexible tack tube 84 connected to the usual separator mechanism.

In order to assist further in steadyng the wiper and tacker mechanism, each casting 42 has an arm 86 which extends in substantially parallel relation to the wiper plane and as the wipers close in passes over a surface formed on a portion of the frame, this arm being useful in resisting the downward thrust which occurs during the stretching of the upper as hereinafter described.

It will be understood that the wipers are secured directly to their carriers by suitable means which permits them to be readily detached when different wipers are to be substituted, such connecting means being supplemented by the connections through the tackers which are mounted in the rectilinear guideways 26, as hereinbefore explained. As shown in Fig. 3, the wipers when fully opened abut along a line extending lengthwise of the shoe, and the point where the operative edges of the wipers meet is displaced but little forwardly of a line connecting the opposite extremities of these edges. The wiper edges have formed in them a continuous groove 88 in which the binder wire lies during the operation of the wipers. Different wipers are provided for different styles and sizes of shoes, and the rectilinear guideways 26 are so disposed in relation to the operative edges of the various wipers that the tackers will be correctly located in positions to be secured to the different wipers, whatever wipers are used.

The upper clamping plunger 90 has a curved foot 92 (Figs. 9 and 10) to clamp the margin of the upper materials flat upon the upper surface of the wipers when the latter are advanced and closed in to embrace the toe of the shoe. The last depressing plunger 94 has a foot 96 with three triangularly spaced surfaces to engage the sole or insole on the bottom of the last near the toe end. The plunger 90 has a transverse swivel pin 98 through which passes an operating rod 100 having fast thereon collars 102 and 104 at opposite sides of the pin, a spring 106 being confined between the pin and the upper collar 102. The last depressing plunger 94 is made in two parts threaded one into the other to permit adjustment of the position to which the last is depressed by adjustment of the length of the plunger. The upper end of the plunger operating rod 100 is pivoted to one corner of a triangular plate 108 another corner of which is pivoted to one of the lower corners of a second triangular plate 110, the other lower corner of the latter being pivoted to the top of the last depressing member 94. The second triangular plate 110 is pivoted (Fig. 1) to one arm of a bell crank lever 112 which is pivoted on the frame of the machine and the other arm of which is connected by a link 114 to the front end of a lever 116 corresponding to the lever hertofore used in ma-

chines of the McFeely type for operating the toe gripper. The rear end of this lever in the present machine is positively connected to the usual toe gripper operating cam slide by means of a link 118.

When the plate 110 is depressed by the upward movement of the front end of the lever 116, the foot 96 and the curved foot 92 are moved downwardly to engage respectively the sole or insole and the margin of the upper outspread over the wipers and by continued movement clamp the upper upon the wipers and positively depress the last to pull and stretch the upper about the toe of the last. In this operation the margin of the upper is yieldingly clamped through compression of the spring 106, and as the last is depressed the upper is permitted to slip between the clamp member and the wipers as required in response to excess of tension at different points. The triangular plate 108 is at this time prevented from turning by means of a finger 120 the rear end of which is in engagement with the front end of the usual rack bar member 122 which in this type of machine controls the closing in and spreading apart of the grippers and tackers. When this rack bar member retires to permit inward movement of the side grippers and tackers, the plate 108 is permitted to swing about its pivotal connection with the plate 110 till the collar 104 engages the pin 98, thus relieving the margin of the upper of the pressure applied by the spring 106. Connected however to an arm of the finger 120 is a lighter spring 124 which at its front end is connected to a hook 126 (Fig. 1) passing through a pin 128 mounted in the frame member 6, the hook being adjustable by means of a nut 130. By its connection through the finger 120 to the upper corner of the plate 108 the spring 124 thus applies a yielding downward pressure to the plunger rod 100, causing the foot 92 to continue to hold the margin of the upper yieldingly for the overwiping operation but under less pressure than applied by compression of the spring 106 in the upper pulling operation.

The rack bar 36, to which the wipers are connected as hereinbefore explained, is operated by a gear segment 132 (Fig. 1) which is pivoted on the frame casting 2. This segment is operated by a link 134 pivoted to an arm 136 fast on a transverse shaft 138, this shaft having fast thereon a gear segment 140 connected to the upper end of a vertical rack bar 142. The lower end of this rack bar is engaged by a second gear segment 144 formed on one arm of a bell crank lever 146 which is pivoted on the frame and the other arm of which carries a swivel pin 148. Through the pin 148 passes an operating rod 150 the front end of which is connected at 160 to the usual heel rest operating

cam slide 161. Between the pin 148 and collars on the ends of the rod 150 are compression springs 162 through which movements are imparted yieldingly to the bell 5 crank lever 146. Also fast on the shaft 138 is an arm 164 provided with a ratchet toothed segment 166, and free to swing on the shaft 138 is a lever 168 one arm of which carries spring pressed pivoted pawls 170 10 adapted in certain relative positions of the arm 164 and the lever 168 to engage the teeth on the arm 164. These teeth and the pawls are so arranged as to permit the pawls to turn the shaft 138 positively in a direction to force the wiper operating rack bar 36 inwardly toward the shoe for imparting to the wipers their final overwiping movement over the bottom of the last. The pawls 170 have cam shaped tails 172 arranged to 15 engage a pin 174 which in certain positions of the lever 168 raises the pawls from the teeth. This lever 168 has a second short arm 176 formed as a gear segment meshing with a second segment 178 formed on one 20 arm of a lever 180 pivoted on the frame. The other arm of the lever 180 carries a cam roll 182 mounted on an eccentric stud 184, this roll being arranged to engage a cam 186 formed on a plate secured to the rocking 25 lever 188 by which in this type of machine the rack bar 122 and associated parts are operated to cause the inward swinging movement of the grippers and tackers as hereinbefore explained.

30 35 It will be understood that it is by the movement of the lever 188 at the time when the side grippers and tackers are swung inwardly that the lever 168 is operated to impart through the pawl and ratchet device 170, 166 the final operative movement to the wiper operating connections. The eccentric stud 184 has on its end an arm 190 carrying a spring pressed plunger by the engagement 40 of which with one of a series of holes 192 in an arc member 194 on the arm 180 the roll 182 may be held in different adjusted 45 positions, thereby controlling through engagement of the roll with the cam 186 the initial position of the lever 168 and of the pawls 170 and their tails 172 in relation to the pin 174. This serves to determine the 50 point in the stroke of the lever 168 when the pawls will come into operative engagement with the ratchet teeth on the arm 164 and thus to determine the extent of movement imparted by this mechanism to the 55 wipers.

55 60 Each pinion 68 which rotates the driver bar guide 52 is connected by a flexible shaft 72 to a beveled pinion 196 (Fig. 1) on a short shaft 198 mounted in bearings in the frame, this pinion being rotated by a gear segment 200 fast on a second shaft 202. Fast on the shaft 202 is also a pinion 204 65 engaging a rack bar 206 on the upper end of a rod 208 which at its lower end has a roll 210 riding on a cam 212 fast on a counter-shaft 214 which is driven by the main cam shaft through a pinion connection. This cam has a gradual rise for imparting 70 the turning movement to the guides 52 to twist the wire about the tacks and a quick drop to return the parts to normal position. The roll 210 may, if desired, be held to its cam by a suitable spring (not shown). 75

75 80 Each driver 54 is operated against the resistance of its spring 76 by a lateral extension member 216 (Fig. 1) on the nearest side driver bar, this member engaging the cap 81 on the top of the member 56 to force 85 the latter downwardly. The extension 216 is pivoted on the side driver bar to swing about an axis parallel to the bar and is held initially in an outwardly swung position by suitable spring and stop mechanism 217, 219, the extension having on its lower end a lug offset inwardly and engaged by the cap 81 on the member 56 as the wipers and their tackers are swung inwardly, each tacker thus picking up its operating member 216 90 and carrying it inwardly into tacking position. This arrangement renders the operating means adaptable to different positions of the wipers and tackers as required for different styles and sizes of shoes. 95

95 100 The wire is fed to the groove 88 in the wipers 24 through the passage 62 in the tack finger of one of the tackers and into the passage in the other tacker by automatic feed mechanism which is omitted from the general view (Fig. 1) but is shown in detail in Figs. 11, 12 and 13. By reference to Fig. 1 it will be noted that the frame casting 2 has slideways 218 extending inwardly toward the position occupied by one 105 of the tackers on the wipers in a plane substantially parallel to the wiper plane. Slidingly mounted in these guideways is a frame 110 220 (Figs. 11 and 12) having in it bearings for various operating shafts and plungers. One of the shafts, 222, has frictionally connected to it a pinion 224 which engages a rack 226 slidingly mounted in a guideway 228 in the frame member 2 and limited in its sliding movement by stops 230 and 232. On the same shaft 222 is a second pinion 234 which is fast on the shaft and engages a pinion 236 on a second shaft 238. The shaft 238 at its upper end is threaded into its bearing, and the pinion 236 has a splined connection 240 with the shaft, permitting the shaft to move lengthwise through the pinion. The lower end of the shaft 238 has teeth 242 arranged to engage, when the shaft has been screwed downwardly for a predetermined distance, with teeth 244 on the upper end of a plunger 246. This plunger is bored axially to receive the upper end of a shaft 248 to which it is splined, the connection permitting the plunger 246 to be adjusted ver- 115 120 125 130

8

tically in relation to the shaft 248 which it drives. The position of the plunger 246 is controlled by a spring 250, which urges it upwardly, and by a cam roll 252 which is guided for vertical movement and has a stud engaging in a peripheral groove in the plunger. The roll 252 is arranged to engage a cam surface 254 against which it is held by the pressure of the spring 250, this cam surface extending along a portion of the frame 2 in approximately parallel relation to the guideway 218. Fast on the lower end of the shaft 248 is a wire feed roll 256 which enters a cutaway portion in the side of a wire throat 258 (Fig. 12). A second roll 260, which is mounted on a lever 261 pivoted on the frame 220, is arranged to engage yieldingly with the other side of the wire, the lever 261 being controlled by a spring 263. The throat 258 may have any well-known clutch device to prevent reverse feed of the wire. The wire is supplied from a reel 262 carried by the frame 220, and it is severed at the outlet end of the throat 258 by the shearing cut of a nicked rotary cutter 264 through the nick in which the wire is fed. This cutter is fast on the end of a shaft 266 in the same plane as the throat but inclined to the throat and having at its outer end an arm 268 by which the shaft may be rocked to sever the wire either manually or by the action on the arm of a plunger 270. This plunger is operated at the end of the wire feed by means of a cam 272 on a pinion 274 which is fast on the driving shaft 276 and engages the pinion 234 on the shaft 222.

The feeding and severing of the wire takes place as the machine comes to a stop after completing its cycle of operations on the shoe, the mechanism for driving the shaft 276 of the wire feeding means being operated and controlled automatically by mechanism hereinafter described to turn the shaft first in one direction and then in the reverse direction. As the shaft 276 begins to turn it drives the shaft 222 and the shaft 238, and also drives frictionally the pinion 224 which engages the rack 226. This pinion first slides the rack outwardly to its limit of movement determined by the stop 232 and then by continued movement acts to force the frame 220 and its supported mechanism inwardly along the guideways 218 until the frame engages the tacker mounted on the wiper on that side of the machine, whereupon the pinion 224 ceases to rotate. In the meantime the shaft 238 is turned by the pinion 236 with a downward movement due to the action of its threaded upper end on the threaded bearing, such downward movement of the shaft continuing as long as the driving shaft 276 continues to rotate in the initial direction. It will be evident that the time when the teeth 242 of the shaft 238

engage the teeth 244 of the wire feed plunger 246 depends upon the vertical position of this plunger which is determined by the action of the cam face 254 on the roll 252, and furthermore that the position of this roll, determined by the cam face, depends upon how far the frame 220 has been moved inwardly before being stopped by the tacker. It will also be evident that the extent of inward movement of the frame will be different for different sets of wipers, the frame moving farther inwardly when the machine is equipped with wipers for operating on a small size shoe than when wipers are used for operating on a larger shoe because the tacker is positioned farther inwardly. The extent of the effective feeding movement of the wire feed plunger 246 and its shaft 248 in proportion to the uniform movement of the driving shaft 276 is thus regulated automatically to feed the correct length of wire required for different sizes of shoes.

It will be understood that when the shaft 238 becomes clutched to the plunger 246 feeding movement is imparted to the wire feed roll 256 and continues until the shaft 276 ceases to turn in the initial direction. The wire passes into the opening 62 in the nearer tacker, this opening being directly in line with the throat 258, and then along the smooth sweep of the wiper groove 88 and into the opening in the other tacker. As the driving shaft 276 comes to the end of its movement the cam 272 meets the upper end 286 of the plunger 270, which is pivoted on the main part of the plunger and is normally held by a spring in alignment therewith, and turns the end of the plunger about its pivot without depressing the plunger. The shaft then reverses its movement, and while the lost motion between the rack 226 and the stop 232 is being taken up, the cam 272 depresses the plunger 270 to effect the cutting of the wire. As the parts thus reverse their movements, the ratchet teeth 242 are permitted to slip over the ratchet teeth 244 until the shaft 238 has been turned upwardly to disengage the teeth. When the shaft 276 arrives at the end of its reverse movement the shaft 238 is returned to its initial upper position and the frame 220 is moved outwardly to its initial position to afford room for the subsequent operation of the wipers on another shoe.

The required movements may be imparted to the shaft 276 by any suitable mechanism, the construction illustrated comprising a constantly running electric motor 290 arranged to drive the shaft in its reverse directions through clutch controlled reversing gear mechanism shown in Fig. 1. The shaft 276 is connected by flexible shafting 292 to a short shaft 294 having thereon a beveled pinion 296 in engagement with a gear seg-

ment 298 loosely mounted on the shaft 202 and having fast thereon a pinion 300 which is operatively engaged with a gear segment 302 on the end of a lever arm 304 pivotally mounted on the frame. The arm 304 has a slot in which is mounted a pin 306 carried by a disk 308 which is fast with a pinion 310, the latter having operative engagement with a worm 312 fast on a shaft 314. Splined on the shaft 314 is a clutch member 316 which is arranged to engage a co-operating member 318 on the shaft of the motor 290. For controlling the clutch member 316 a pivoted bar 320 is provided which is connected with the clutch member and has at its upper end an offset lug 322 arranged normally to extend into a notch in a controlling disk 324 which is fast with the pinion 310. On one side of the bar 320 is a projection 326 which is arranged to be engaged by a spring plunger 328 mounted in the outer end of the lever arm 136 through which movement is imparted to the wiper operating link 134. As this lever arm returns to its initial position just before the machine comes to a stop, the spring plunger 328 engages the side of the lug 326 and swings the bar 320 rearwardly against the resistance of a spring 330, withdrawing the lug 322 from the notch in the disk 324 and at the same time carrying the clutch member 316 into engagement with the member 318. The motor is then effective to turn the pinion 310 and the connections to the shaft 276 and continues to do so until the pinion has completed a revolution, the pin and slot connection to the lever arm 304 acting to swing this arm first in one direction and then in the reverse direction for imparting similar reverse movements to the gear segment 298. It will be understood that the spring plunger 328 slips past the lug 326 on the bar 320 and immediately releases the bar, thus permitting the lug 322 again to enter the notch in the controlling disk to disconnect the clutch when the pinion 310 has completed a revolution. When the arm 136 receives its wiper operating movement the spring plunger 328 yields without effect upon the member 326 which it engages.

In the operation of the machine, the operator presents the shoe with the sole or insole in engagement with the shoe rest 278 which in the present machine is arranged to engage the shoe farther rearwardly than is usual and has a rounded shoe engaging surface. Forwardly of the shoe rest the sole engages the last depressing member 96, and the toe end of the last is presented in engagement with the concave inner surface of the foot 92. The margin of the upper is positioned in the open side grippers, and its toe portion is outspread under the foot 92, the wipers at this time being retracted from the shoe. The machine is then started,

and the main cam shaft makes a partial revolution and then comes automatically to rest. In this stage of the cycle the side grippers grip and pull the upper across the forepart of the last with a force determined by adjustment of the usual updraw springs, and preferably give it also a fore-drawing stretch as common heretofore in many machines of the illustrated type, the heel rest 280 in the meantime being moved forward into yielding engagement with the shoe by the operation of the cam slide 161. By the operation of the segment 132 through its yielding connection with this cam slide forward movement is at the same time imparted to the rack bar 36 and to the arcuate slides 14, the friction between these slides and the wiper head, which may be increased by any well-known means if found desirable, causing the wiper head first to be advanced bodily toward the shoe before the wipers begin to close. The forward movement of the wiper head is arrested, when the wipers have been advanced substantially to the end of the toe, by the engagement of a yielding plunger 282 (Fig. 2) on the wiper head with a portion of the frame of the machine. The continued movement of the rack bar 36 then causes the wipers to close about the toe of the shoe through the rack and pinion connections 18 and 20, the closing movement of the wipers continuing until the tackers which they carry engage the sides of the toe of the shoe, the position of the wipers at this time being somewhat below the plane of the shoe bottom. Further movement of the wiper operating connections is then taken up by the yield of one of the springs 162. It will be understood that in this preliminary movement of the wiper operating means the lever arm 164 is swung rearwardly to carry its ratchet teeth into position to be engaged subsequently by the pawls 170.

While the machine is at rest with the wipers thus positioned the operator is enabled to make any of the usual adjustments, for example to straighten the tip by relative movement of the side grippers, the toe portion of the upper being still free to permit the tip straightening or other adjustment of the upper to be effected without any tendency to twist or wrinkle the upper about the toe.

Upon the subsequent starting of the machine the lever 116 receives its operative movement, thereby clamping the margin of the upper outspread upon the wipers by the action of the foot 92 and forcing the toe end of the last downwardly by the action of the member 96, the upper being thus pulled and stretched and also wiped tightly and smoothly over the last and close to the sides of the last round the toe end, its margin being permitted to slip

and give up stock at different points under yielding control of the foot 92. In its depression the last rocks somewhat about the rounded sole rest 278, and in order to permit such rocking movement the heel rest 280 of the present machine is not locked until a later time in the cycle than in prior machines. The depression of the last continues until the margin of the sole or insole is positioned slightly below the level of the wipers, and the usual side clamp arms 279 are then swung inwardly into position to support the shoe for the overwiping and tacking operations.

15 As soon as the last has been pressed below the wipers, the wipers and their tackers are released by the shoe, and that one of the springs 162 which was compressed by the excess movement of the wiper operating means is then permitted to act to advance and close the wipers over the shoe bottom, the spring plunger 282 yielding to permit the advancing movement. At this time, by the retractive movement of the member 122 and its connections, the side grippers are permitted to move inwardly and the side tackers and their wipers also are moved inwardly to overlay the upper as usual at the sides of the forepart, the side tack driver bars 7 being finally tripped to cause them to drive the side tacks. The rearward movement of the member 122, by its control of the finger 120, causes the clamp member 92 to relax its pressure on the margin of the upper, as hereinbefore explained, to permit the margin to slip more freely under control of the spring 124 in the overwiping operation. The advancing and closing movement of the wipers is completed positively, 40 through the pawl and ratchet device 170, 166 operated as hereinbefore explained by the movement of the lever 188 whereby the retractive movement of the member 122 is effected. The side tack driver bars are not tripped until the wipers have completed their advancing and closing movements, the caps 81 on the toe tackers being then positioned under the operating members 216 on the driver bars, and when these bars are 45 operated the tacks at the sides of the toe for fastening the binder are driven simultaneously with the other tacks. The mechanism for rotating the driver bar guides 52 then begins to act, and the tack fingers by their 50 rotative movements serve to tighten the wire round the toe and then to twist its ends about the partially driven tacks. The guides 52 rotate in opposite directions, and the flared ends of the passages 62 first move 55 toward each other and toward the heel end of the shoe to tighten the wire, the continued rotation of the guides and their coincident upward movement serving to twist the tightened wire several times round the 60 tacks, stripping the wire first gradually 65

down the hemispherical ends of the tack fingers and then entirely out of the passages, the tack fingers being raised above the heads of the tacks. The various parts of the machine are then returned to their starting positions, the tack fingers moving outwardly to clear the tacks before they are again screwed downward. Just before the machine comes to a stop the wire feeding mechanism is started in operation by the action of the spring plunger 328 on the controlling bar 320, and the wire is fed into the wipers and tackers and cut off to leave a toe binder in place ready for the operation upon the next shoe.

Having described the invention, what I claim as new and desire to secure by Letters Patent of the United States is:

1. A machine of the class described having, in combination, means for pulling an upper at the sides of the forepart to stretch it transversely over a last to substantially its final tension before the upper is pulled at the end of the toe, and means for pulling the upper at the end of the toe to stretch it lengthwise of the last after the transverse pull has been substantially completed.

2. A machine of the class described having, in combination, grippers for engaging an upper at opposite sides of a last, operating means for effecting relative movement of said grippers and the last to pull the upper transversely over the last while leaving the upper substantially free about the end of the toe, a device for gripping the upper at the end of the toe, and operating means for effecting relative movement of said device and the last to stretch the upper lengthwise after the upper has been subjected to substantially its final transverse tension by the side grippers.

3. A machine of the class described constructed to perform its cycle of operations in a plurality of stages after each of which the machine comes automatically to rest having, in combination, means for pulling an upper at the opposite sides of the forepart to stretch it transversely over a last in one stage of the cycle, and means for pulling the upper at the end of the toe to stretch it lengthwise in a different stage of the cycle.

4. A machine of the class described having, in combination, power means automatically operative to pull an upper at the opposite sides of the forepart to stretch it transversely over a last and to come to a stop with the upper held under transverse tension to permit it to be adjusted relatively to the last, and means automatically operative upon a subsequent starting of the machine to grip and pull the upper at the toe end of the last.

5. A machine of the class described having, in combination, means for gripping and

- pulling an upper to substantially its final tension at the sides of the forepart while leaving the margin of the upper substantially free about the end of the toe to permit 5 the transversely tensioned upper to be adjusted before it is gripped at the toe, and means for thereafter gripping and pulling the upper at the end of the toe to stretch it lengthwise of the last.
- 10 6. A machine of the class described having, in combination, grippers and means for operating them to pull an upper at the opposite sides of the forepart of a last, means for clamping the upper about the 15 end of the toe, and operating means for moving the last relatively to said clamping means to pull the upper after the pull at the sides has been substantially completed and while the upper is held under tension 20 by the side grippers.
7. A machine of the class described having, in combination, means for pulling an upper at the sides of the forepart to stretch it transversely over a last while the upper 25 is substantially free about the toe and for then holding the upper under tension to permit it to be adjusted relatively to the last, clamping means constructed to clamp the margin of the upper round the toe from 30 one side of the toe to the other side, and mechanism for operating said clamping means to clamp the upper and for effecting relative movement between the last and the clamping means to pull the upper at the 35 toe after the upper has been adjusted on the last.
8. A machine of the class described having, in combination, means for pulling an upper at the opposite sides of the forepart 40 of a last, means for clamping the upper yieldingly about the end of the toe, and operating means for effecting relative movement of said clamping means and the last to pull the upper at the toe after the upper 45 has been pulled at the sides of the last, the clamping means being constructed to permit the margin of the upper to slip at different points in response to excess of pulling tension.
- 50 9. A machine of the class described having, in combination, power operated means automatically operative to pull an upper over a last at the sides of the forepart and then to come to a stop with the upper held 55 under tension, and means operative upon a subsequent starting of the machine to clamp the upper yieldingly about the end of the toe and to pull the upper over the toe while permitting it to slip to equalize the pulling 60 tension at different points about the toe.
10. A machine of the class described having, in combination, means for pulling an upper at the sides of the forepart to stretch the upper transversely over a last to substantially 65 its final tension before it is pulled at the toe, means for pulling the upper at the end of the toe to stretch it lengthwise after the pull at the sides has been substantially completed, and means for wiping the upper inwardly over the bottom of the last after it has been pulled at the sides and at the toe.
11. A machine of the class described having, in combination, power operated means automatically operative to pull an upper at 70 the sides of the forepart and to come to a stop with the upper held under tension, and means automatically operative upon a subsequent starting of the machine to pull the upper at the end of the toe and then to 75 wipe the margin of the upper into lasted position about the toe and fasten it.
12. A machine of the class described having, in combination, means for pulling an upper at the sides of the forepart of a last 80 while leaving the upper substantially free about the end of the toe and for then holding the upper under tension to permit it to be adjusted relatively to the last while it is free at the toe, a device for clamping the 85 upper about the end of the toe, operating means for effecting relative movement of said clamping device and the last to pull the upper at the toe after it has been adjusted on the last, and mechanism automatically 90 operative in time relation to the pulling of the upper at the toe to wipe the upper into lasted position about the toe.
13. A machine of the class described having, in combination, means for pulling an upper at the sides of the forepart of a last, a device for clamping the upper about the toe, operating means for effecting relative movement of said clamping device and the last to pull the upper at the toe after it has 100 been pulled at the sides, means for wiping the upper inwardly over the bottom of the last, and a controlling device automatically 105 operative to relax the clamping pressure on the upper while maintaining it under control of the clamping device in the overwiping operation.
14. A machine of the class described having, in combination, means for pulling an upper at the opposite sides of the forepart of a last, toe embracing wipers mounted for advancing and closing movements to wipe the upper inwardly over the bottom of the last about the toe, a device for clamping the upper on said wipers, and means for 110 effecting relative movement between the last and said wipers and clamping device to pull the upper over the toe of the last before it is wiped inwardly by the wipers.
15. A machine of the class described having, in combination, means for pulling an upper at the opposite sides of the forepart of a last, toe embracing wipers for wiping the upper into lasted position about the toe, a device for clamping the upper yieldingly 115
- 120
- 125
- 130

on said wipers, means for effecting relative movement between the last and said wipers and clamping device transversely of the plane of the last bottom to pull the upper at the toe while permitting the upper to slip at different points in response to excess of tension, means for closing the wipers inwardly over the bottom of the last, and means for maintaining said clamping device in position to control the margin of the upper as it is wiped inwardly by the wipers while permitting the upper to slip in response to the pull of the wipers.

16. A machine of the class described having, in combination, means for pulling an upper at the opposite sides of the forepart of a last, toe embracing wipers mounted for advancing and closing movements to wipe the upper inwardly over the bottom of the last about the toe, a device for clamping the upper yieldingly on said wipers, means for effecting relative movement between the last and said wipers and clamping device transversely of the plane of the last bottom to pull the upper over the toe while permitting the upper to slip to equalize the tension at different points about the toe, and controlling means for relaxing the clamping pressure on the upper while maintaining it under control of said clamping device in the overwiping operation of the wipers.

17. A machine of the class described having, in combination, means for pulling an upper at the opposite sides of the forepart of a last while leaving the upper substantially free from tension about the toe end of the last, toe embracing wipers for wiping the upper inwardly over the bottom of the last about the toe, a device for clamping the upper on said wipers, and means for effecting relative movement between the last and said wipers and clamping device to pull the upper over the toe of the last before it is wiped inwardly over the bottom of the last.

45 18. A machine of the class described having, in combination, means for pulling an upper at the opposite sides of the forepart of a last while leaving the margin of the upper substantially free about the end of the toe and for then holding the upper under tension with the machine at rest to permit the upper to be adjusted on the last, toe embracing wipers for wiping the upper inwardly over the bottom of the last about the toe, power operated means for clamping the upper on said wipers and for effecting relative movement between the last and said wipers and clamping means to pull the upper over the toe upon a subsequent starting of the machine, and power means for operating the wipers subsequently to wipe the upper inwardly over the bottom of the last.

19. A machine of the class described having, in combination, means for pulling an

upper at the opposite sides of the forepart 65 of a last and for then holding the upper under tension with the machine at rest, toe embracing wipers for wiping the upper inwardly over the bottom of the last about the toe, a device for clamping the upper yieldingly 70 on the wipers, operating means for effecting relative movement between the last and said wipers and clamping device to pull the upper over the toe of the last upon a subsequent starting of the machine, means 75 for closing the wipers inwardly over the bottom of the last, and mechanism for controlling said clamping device to relax the clamping pressure on the upper automatically 80 while maintaining the upper under control of said device in the overwiping operation.

20. A machine of the class described having, in combination, means for pulling an upper at the opposite sides of the forepart 85 of a last, toe embracing wipers for wiping the upper inwardly over the bottom of the last, means for closing said wipers about the toe of the last, and means for thereafter clamping the upper upon the wipers and 90 for pulling the upper over the toe of the last by relative movement between the last and the wipers before the upper is wiped inwardly over the bottom of the last.

21. A machine of the class described having, in combination, means for pulling an upper at the opposite sides of the forepart of a last, toe embracing wipers for wiping the upper inwardly over the bottom of the last about the toe, means for closing said wipers 100 round the toe of the last in time relation to the pulling of the upper at the sides, a device for clamping the upper upon the wipers, and means for operating said clamping device to clamp the upper and for effecting relative 105 movement between the last and the wipers and clamping device to pull the upper at the toe of the last before the upper is wiped inwardly by the wipers.

22. A machine of the class described having, in combination, power operated means for pulling an upper at the opposite sides of the forepart of a last and for then holding the upper under tension with the machine at rest, toe embracing wipers for wiping the upper inwardly over the bottom of the last about the toe, means for advancing and closing said wipers yieldingly about the toe below the plane of the last bottom in 110 time relation to the pulling of the upper at the sides, and means operative upon a subsequent starting of the machine to clamp the upper upon the wipers and to depress the last for pulling the upper over the toe 115 before it is wiped inwardly over the bottom of the last.

23. A machine of the class described having, in combination, means for pulling an

- upper at the opposite sides of the forepart of a last, toe embracing wipers for wiping the upper inwardly over the bottom of the last about the toe, operating means for closing the wipers yieldingly about the toe below the plane of the last bottom including a yielding element operative subsequently to impart overwiping movement to the wipers, a device for clamping the upper on the wipers, and means for depressing the last relatively to the wipers and said clamping device to pull the upper over the toe and to position the shoe in a plane to receive the overwiping action of the wipers. 65
- 10 24. A machine of the class described having, in combination, means for pulling an upper at the opposite sides of the forepart of a last, toe embracing wipers for wiping the upper inwardly over the bottom of the last, means for closing said wipers yieldingly about the toe as the upper is pulled at the sides, means for clamping the upper upon the wipers and for effecting relative movement between the last and the wipers to 70 pull the upper and to position the shoe and the wipers relatively for the overwiping operation, and additional means for subsequently closing the wipers inwardly over the bottom of the last. 75
- 15 25. A machine of the class described having, in combination, means for pulling an upper at the opposite sides of the forepart of a last, toe embracing wipers for wiping the upper inwardly over the bottom of the last, operating means for closing the wipers yieldingly about the toe below the plane of the last bottom including a yielding element operative subsequently to impart overwiping movement to the wipers, means for 80 clamping the upper on the wipers and for effecting relative movement of the last and the wipers transversely of the plane of the last bottom to pull the upper and to position the shoe and the wipers relatively for the overwiping operation, and positive means for completing the overwiping movement of the wipers. 85
- 20 26. A machine of the class described having, in combination, means for pulling an upper at the opposite sides of the forepart of a last, toe embracing wipers for wiping the upper inwardly over the bottom of the last, means for clamping the upper upon the wipers and for effecting relative movement of the last and the wipers transversely of the plane of the last bottom to pull the upper, and operating means for imparting overwiping movement to the wipers first yieldingly and then positively. 90
- 25 27. A machine of the class described having, in combination, means for pulling an upper at the opposite sides of the forepart of a last, toe embracing wipers for wiping the upper inwardly over the bottom of the last, operating means for closing the wipers yieldingly about the toe as the upper is pulled at the sides, means for thereafter clamping the upper upon the wipers and for effecting a relative movement of the last and the wipers transversely of the plane of the last bottom to pull the upper, and pawl and ratchet mechanism operative subsequently to impart a predetermined overwiping movement to the wipers. 95
- 30 28. A machine of the class described having, in combination, side grippers for pulling an upper at the sides of the forepart of a last, toe embracing wipers for wiping the upper inwardly over the bottom of the last, operating means for closing the wipers inwardly about the toe as the upper is pulled by the side grippers, means for causing the side grippers subsequently to overdraw the upper, and additional wiper operating means operative in the overdrawing movement of said grippers to impart overwiping movement to the wipers. 100
- 35 29. A machine of the class described having, in combination, means for pulling an upper over a last, toe embracing wipers for wiping the upper inwardly over the bottom of the last, operating means for closing said wipers yieldingly about the toe, a member arranged to be moved idly by said operating means as the wipers are closed about the toe, and a device operative subsequently through said member to impart further closing movement to the wipers. 105
- 40 30. A machine of the class described having, in combination, means for pulling an upper over a last, toe embracing wipers for wiping the upper inwardly over the bottom of the last, operating means for closing said wipers yieldingly about the toe, a member arranged to be moved idly by said operating means as the wipers are closed about the toe and having ratchet teeth thereon, and additional wiper closing means comprising a pawl arranged to engage said ratchet teeth and to impart further movement to the wipers through said member. 110
- 45 31. A machine of the class described having, in combination, means for pulling an upper over a last, toe embracing wipers for wiping the upper inwardly over the bottom of the last, operating means for closing the wipers yieldingly about the toe, additional wiper operating means for imparting closing movement positively to the wipers, and means for varying the extent of said positive closing movement. 115
- 50 32. A machine of the class described having, in combination, means automatically operative to pull an upper over a last and to come to a stop with the upper held under tension, toe embracing wipers for wiping the upper inwardly over the bottom of the last, operating means for closing said wipers 120
- 55 60 65 70 75 80 85 90 95 100 105 110 115 120 125

about the toe in the upper pulling operation, and additional wiper operating means operative upon a subsequent starting of the machine to impart overwiping movement to the wipers.

33. A machine of the class described having, in combination, upper pulling means automatically operative to pull an upper over a last and to come to a stop with the upper held under tension, wipers for embracing the toe of the shoe, and means automatically operative upon a subsequent starting of the machine to effect relative movement of the wipers and the last transversely of the plane of the last bottom to upwipe the upper and then to close the wipers inwardly over the bottom of the last.

34. A machine of the class described having, in combination, means automatically operative to pull an upper over a last and to come to a stop with the upper held under tension, wipers for embracing the toe of the shoe, means for closing said wipers yielding inward about the toe as the upper is pulled, and means automatically operative upon a subsequent starting of the machine to effect relative movement of the last and the wipers transversely of the plane of the last bottom to upwipe the upper.

35. A machine of the class described having, in combination, means for pulling an upper over the last, wipers for embracing the toe of the shoe, means for closing the wipers inwardly about the toe, operating means for effecting relative movement of the wipers and the last transversely of the plane of the last bottom to upwipe the upper, and means for clamping the upper upon the wipers in the upwiping operation to pull the upper over the toe.

36. A machine of the class described having, in combination, means for pulling an upper at the sides of the forepart of a last while leaving the upper substantially free round the end of the toe, wipers for embracing the toe of the shoe, means for closing said wipers inwardly about the toe, means for effecting relative movement of the wipers and the last transversely of the plane of the last bottom after the upper has been pulled at the sides to wipe the upper toward the edge of the sole, and means for thereafter closing the wipers inwardly over the bottom of the last.

37. A machine of the class described having, in combination, means for pulling an upper over a last, wipers for embracing the toe of the shoe, means for effecting relative movement of the wipers and the last transversely of the plane of the last bottom to upwipe the upper, means for thereafter closing the wipers inwardly over the bottom of the last, and means operative in time relation to the wipers to fasten the upper in lasted position.

38. A machine of the class described having, in combination, means automatically operative to pull an upper over a last and to come to a stop with the upper held under tension and lasting means automatically operative upon a subsequent starting of the machine to upwipe and overwipe the upper and to fasten the upper in lasted position about the toe.

39. A machine of the class described having, in combination, means for pulling an upper over a last, wipers for embracing the toe of the shoe, a device for clamping the upper upon the wipers, and operating means for moving the wipers relatively to said clamping device to advance them lengthwise of the shoe and to close them inward laterally of the shoe to overwipe the upper.

40. A machine of the class described having, in combination, means for pulling an upper at the sides of the forepart of a last while leaving the upper substantially free round the end of the toe, wipers for embracing the toe of the shoe, a clamping device comprising a member constructed for substantially continuous engagement with the upper round the toe from one side of the toe to the other side to clamp the upper upon the wipers, means for effecting relative movement between the last and said wipers and clamping device transversely of the plane of the last bottom to pull the upper, and means for thereafter moving the wipers relatively to said clamping device to advance and close them inwardly over the bottom of the last to overwipe the upper.

41. A machine of the class described having, in combination, means for pulling an upper over a last, wipers for embracing the toe of the shoe, means movable lengthwise of the shoe for advancing and closing said wipers inwardly over the bottom of the last to overwipe the upper and for applying a binder about the toe to hold the upper in overwiped position, and means automatically operative in time relation to said wipers to fasten the ends of the binder to anchor tacks at the sides of the shoe.

42. A machine of the class described having, in combination, means for pulling an upper over a last, wipers for embracing the toe of the shoe, power means for advancing and closing said wipers inwardly over the bottom of the last to overwipe the upper and for pressing a binder inwardly about the toe to hold the upper in overwiped position, and means for fastening the ends of the binder to anchor tacks at the sides of the shoe.

43. A machine of the class described having, in combination, means for pulling an upper over a last, toe embracing wipers and means for closing them inwardly to wipe the upper into lasted position about the toe, and mechanism forming a unit with the

- wipers to move inwardly with them and automatically operative in time relation to the wipers to drive anchor tacks at the sides of the shoe and to twist the ends of a toe 5 binder wire about said tacks.
44. A machine of the class described having, in combination, means automatically operative to pull an upper over a last and to come to a stop with the upper held under 10 tension, toe embracing wipers and means for advancing and closing them inwardly over the bottom of the last upon a subsequent starting of the machine to wipe the upper into lasted position about the toe, and means 15 automatically operative in time relation to the wipers to drive anchor tacks at the sides of the shoe and to twist the ends of a toe binder wire about said tacks.
45. A machine of the class described having, in combination, means for pulling an upper at the sides of the forepart of a last while leaving the upper substantially free about the end of the toe, wipers for embracing the toe of the shoe, a device for 20 clamping the upper upon said wipers, means for effecting relative movement between the last and said wipers and clamping device to pull the upper at the toe after the pull at the sides has been substantially completed, means for operating said wipers to 25 wipe the upper inwardly over the bottom of the last, the wipers being constructed to apply a binder about the toe, and means for twisting the ends of the binder about 30 anchor tacks at the sides of the shoe.
46. In a machine of the class described, the combination with means for pulling an upper over a last, of tackers for driving 35 tacks at the opposite sides of the forepart of the shoe, toe embracing wipers and means for operating them to wipe the upper inwardly about the toe, additional tackers movable with said wipers into position for 40 driving tacks at the sides of the toe, and mechanism operated by said first named tackers for imparting operative movement to said additional tackers.
47. In a machine of the class described, the combination with means for pulling an 45 upper over a last, of tackers for driving tacks at the opposite sides of the forepart of the shoe, toe embracing wipers mounted for advancing and closing movements over the shoe, and additional tackers mounted at 50 the outer ends of said wipers and movable with the wipers inwardly into position for driving tacks in front of said side tackers, the side tackers having thereon members for operating said additional tackers and into 55 operative relation to which said last named tackers are moved as the wipers are closed about the toe.
48. In a machine of the class described, the combination with shoe positioning 60 means, of toe embracing wipers having 65 means for applying a binder about the toe, power operated means for closing said wipers inwardly over the bottom of the shoe to overwipe the upper and to apply the binder, and means for twisting the ends of said binder about anchor tacks at the opposite sides of the shoe simultaneously. 70
49. In a machine of the class described, the combination with shoe positioning means, of toe embracing wipers, power operated means for closing said wipers inwardly over the bottom of the shoe to overwipe the upper and for applying a binder about the toe, and means carried by the wipers and automatically operative in time 75 relation to the wipers to drive anchor tacks at the opposite sides of the shoe and to twist the ends of the binder about said tacks simultaneously. 80
50. In a machine of the class described, the combination with toe embracing wipers mounted for closing movements over a shoe, of tackers secured in fixed relation to said wipers to move with the wipers into operative relation to the shoe, additional tackers 85 movable independently of the wipers, and means for operating said tackers to drive upper fastening tacks at the sides of the shoe. 90
51. In a machine of the class described, the combination with toe embracing wipers mounted for movement inwardly over the toe of a shoe, of binder fastening devices mounted to move inwardly with the wipers and comprising members rotatable to twist 95 the ends of a binder about tacks at the sides of the shoe. 100
52. In a machine of the class described, the combination with wipers mounted for closing movements over the toe of a shoe, of toe binder fastening devices secured in fixed relation to said wipers to close inwardly with the wipers, said devices comprising means for driving anchor tacks at 105 the sides of the shoe and for twisting the ends of the binder about said tacks. 110
53. In a machine of the class described, the combination with shoe positioning means, of toe embracing wipers mounted for closing movements over the shoe and having a groove therein to receive a binder wire, and binder fastening devices mounted in fixed relation to said wipers to move inwardly with the wipers and having means for twisting the ends of the binder about 115 tacks at the sides of the shoe. 120
54. In a machine of the class described, the combination with shoe positioning means, of toe embracing wipers mounted for closing movements over the shoe and having means for positioning a binder wire in predetermined relation to the wiper edges, binder fastening devices mounted in fixed relation to said wipers and having members provided with openings to receive 125 130

- the ends of the binder wire, and means for rotating said members to twist the ends of the binder about tacks at the sides of the shoe.
5. 55. In a machine of the class described, the combination with shoe positioning means, of toe embracing wipers mounted for closing movements over the shoe and having a groove therein to receive and position a binder wire, members mounted in fixed relation to said wipers and having openings arranged to aline with said groove in the wipers, means for feeding binder wire along the groove in the wipers and into said openings, and means for turning said members to twist the ends of the binder about tacks at the sides of the shoe.
10. 56. In a machine of the class described, the combination with shoe positioning means, of toe embracing wipers mounted for closing movements over the shoe, tackers mounted in predetermined relation to said wipers for inward movement with the wipers and comprising tack holders having openings to receive a binder wire, and means for operating said tackers to drive anchor tacks at the sides of the shoe and for turning said tack holders to twist the ends of the binder about the tacks.
15. 57. In a machine of the class described, the combination with means for wiping an upper into lasted position about the toe of a shoe, of devices for fastening the ends of a binder to anchor tacks at the sides of the shoe comprising tack holders having outer rounded end faces provided with openings to receive the binder, and means for turning said tack holders to twist the ends of the binder about the anchor tacks.
20. 58. In a machine of the class described, the combination with means for wiping an upper inwardly about the toe of a shoe, of devices for fastening the ends of a binder to anchor tacks at the opposite sides of the shoe comprising members mounted for turning movement to twist the ends of the binder about the tacks and for movement lengthwise of the tacks during their turning movement.
25. 59. In a machine of the class described, the combination with means for wiping an upper inwardly about the toe of a shoe, of devices for fastening the ends of a binder to anchor tacks at the sides of the shoe comprising tack holders and drivers for forcing tacks partially out of said holders and into the shoe, and means for turning said tack holders to twist the ends of a binder about said tacks and for moving them simultaneously away from the plane of the shoe bottom to clear the tacks.
30. 60. In a machine of the class described, a device for fastening an end of a toe binder to an anchor tack comprising a member rotatable to twist the end of the binder about the tack, and means to cause said member to move lengthwise of the tack as it is turned about the tack.
35. 61. In a machine of the class described, a device for fastening the end of a toe binder to an anchor tack comprising a member rotatable to twist the end of the binder about the tack, and a member having a threaded connection with said rotatable member to cause the latter member to move lengthwise of the tack during its turning movement.
40. 62. In a machine of the class described, a device for anchoring an end of a toe binder to a shoe comprising a pair of tack holding fingers and a tack driver, one of said fingers having an opening to receive the end of the binder, and means for turning said fingers to twist the end of the binder about a tack.
45. 63. In a machine of the class described, a device for anchoring an end of a toe binder to a shoe comprising a pair of tack holding fingers and a tack driver, said fingers having rounded outer ends to face the shoe and one of the fingers having an opening to receive the end of the binder, and means for turning said fingers to twist the end of the binder about a tack and for moving them lengthwise of the tack during their turning movement.
50. 64. In a machine of the class described, the combination with wiper holders constructed to receive wipers of different sizes for lasting the toes of different shoes, of upper fastening means constructed to be secured in fixed relation to the different wipers for movement with them into upper fastening position and to be detached therefrom to permit different wipers to be substituted.
55. 65. In a machine of the class described, the combination with wiper holders constructed to receive wipers of different sizes for lasting the toes of different shoes, of devices for fastening the ends of a toe binder to tacks at the sides of the shoe, and means for positioning said devices in the same predetermined relation to the outer ends of the different wipers, whatever wipers are used, for movement with the wipers into binder fastening position.
60. 66. In a machine of the class described, the combination with wiper holders constructed to receive wipers of different sizes for lasting the toes of different shoes, of devices for fastening the ends of a toe binder to tacks at the sides of the shoe, said devices having binder receiving openings adapted to aline with a binder positioning groove in the wipers, and means for predeterminedly determining the position of said devices with their openings in alinement with the wiper groove irrespective of the size of the wipers.
65. 67. A machine of the class described having, in combination, means for pulling an

- upper over a last, means for wiping the upper into lasted position about the toe and for applying a binder round the toe, devices for twisting the ends of the binder about 5 anchor tacks at the sides of the shoe, and means for feeding binder material into position to be applied to the shoe.
68. A machine of the class described having, in combination, means for pulling an upper over a last, mechanism automatically operative to wipe the upper into lasted position and to fasten a binder to anchor tacks at the sides of the shoe, and power operated binder feeding means arranged to be started 10 in operation automatically at the end of the cycle of operations on a shoe to feed binder material into position to be applied to the next shoe.
69. In a machine of the class described, 20 the combination with shoe positioning means, of means for lasting the toe of the shoe and for applying a binder and twisting its ends about tacks at the opposite sides of the shoe substantially simultaneously, and 25 means for feeding binder material into operative relation to the means for twisting the ends about the tacks.
70. In a machine of the class described, 30 the combination with shoe positioning means, of means for wiping the upper into lasted position about the toe and for applying a binder about the toe and fastening it to anchor tacks at the sides of the shoe, and means automatically operative at the end of 35 the operation of the machine upon a shoe to feed binder material into position to be applied and fastened to tacks in lasting the next shoe.
71. In a machine of the class described, 40 the combination with means for applying binder wire about the toe of a shoe, of mechanism for feeding toe binder wire to said binder applying means, said mechanism being movable bodily toward and from the 45 binder applying means and comprising parts additionally movable to feed the wire to said means.
72. In a machine of the class described, 50 the combination with means for applying binder wire about the toe of a shoe, of means for feeding toe binder wire to said binder applying means comprising a support movable toward and from the binder applying means, and feeding mechanism carried by 55 said support and operative to feed the wire after the support has been moved toward the binder applying means.
73. In a machine of the class described, 60 the combination with toe embracing wipers, of means operative when said wipers are in an idle position to feed toe binder wire into position to be applied to the shoe when the wipers are operated, said feeding means being mounted at one side of the wipers for
- movement toward and from the wipers and 65 comprising mechanism arranged to operate to feed the wire after said feeding means has been moved toward the wipers.
74. In a machine of the class described, 70 the combination with toe lasting means, of means for feeding toe binder wire into position to be applied to a shoe by said lasting means comprising a support movable toward and from the lasting means, and operating mechanism carried by said support for moving it toward and from the lasting means 75 and for effecting feeding movement of the wire in time relation to said movement of the support.
75. In a machine of the class described, 80 the combination with toe lasting means, of mechanism for feeding binder wire to said lasting means, a support upon which said mechanism is mounted, said support being movable toward and from the lasting means, and means operated by said feeding mechanism for moving said support toward the lasting means prior to the feeding movement of the wire and for moving it from the lasting means after the wire has been fed. 85
76. In a machine of the class described, 90 the combination with toe lasting mechanism, of means for feeding binder wire to said lasting mechanism for use in a subsequent operation of said mechanism on a shoe, 95 said feeding means being automatically operative to advance toward the lasting mechanism and then to feed and sever the wire and to retire from the lasting mechanism.
77. In a machine of the class described, 100 the combination with means for applying a binder about the toe of a shoe, of means for feeding binder material to said binder applying means, and means for varying the length of feed of the binder material. 105
78. In a machine of the class described, 110 the combination with means for applying a binder about the toe of a shoe, of means for feeding binder material to said binder applying means, and mechanism automatically operative to determine the length of feed of the binder material in accordance with the size of the shoe.
79. In a machine of the class described, 115 the combination with means for applying a binder about the toe of a shoe, of means for feeding binder material to said binder applying means, said feeding means being mounted for positioning movement relatively to the binder applying means, and mechanism controlled by said positioning movement of the feeding means for determining the length of the feed. 120
80. In a machine of the class described, 125 the combination with means for feeding and applying binder material about the toes of shoes, of controlling mechanism automatically operative to determine the length of the

material applied to each shoe in accordance with the size of the shoe.

81. In a machine of the class described, the combination with toe lasting means comprising a wiper support adapted to receive and position wipers of different sizes for lasting different shoes, of means for feeding binder wire to said lasting means, and mechanism arranged to co-operate with the wiper mechanism to control automatically the length of the feed in accordance with the size of the wipers.

82. In a machine of the class described, the combination with toe lasting means, of mechanism for feeding binder wire to said lasting means, said mechanism being mounted for movement bodily to a position determined by the lasting means before it begins its feeding movement, and means for determining automatically the length of the feed in accordance with the position thus assumed by the feeding mechanism.

83. In a machine of the class described, the combination with toe lasting means comprising a wiper support adapted to receive wipers of different sizes for lasting different shoes, of means for feeding binder wire to said lasting means comprising feeding mechanism movable bodily to a position determined by the size of the wipers and constructed for additional feeding movement, and a device arranged to be adjusted by said bodily movement of the mechanism for determining automatically the length of the feed in accordance with the size of the wipers.

84. A machine of the class described having, in combination, means for pulling an upper over a last, toe embracing wipers, power-operated means for effecting relative movement of said wipers and the last to

upwipe and overwipe the upper, and automatic means for fastening a binder about the toe in time relation to the operation of the wipers on the toe.

45

85. In a machine of the class described, the combination with shoe positioning means and end-embracing wipers, of operating mechanism for closing said wipers about an end of the shoe and for thereafter closing them inwardly over the bottom of the shoe, said operating mechanism comprising spring means arranged to yield in response to resistance of the shoe as the wipers are closed about the end of the shoe and positive means for pressing the wipers unyieldingly inward over the bottom of the shoe.

50

86. In a machine of the class described, the combination with shoe positioning means, end-embracing wipers, and means for effecting relative movement of said shoe positioning means and wipers to wipe the upper heightwise of the toe, of spring means for closing the wipers yieldingly about the toe for the upwiping operation and for thereafter closing them inwardly over the bottom of the shoe, and positive means for completing the inward closing movement of the wipers.

55

87. In a machine of the class described, the combination with shoe positioning means and end-embracing wipers, of operating means for closing said wipers inwardly over the bottom of the shoe first with yielding pressure and then with unyielding pressure, said operating means being adjustable to vary the extent of movement imparted to the wipers by the unyielding pressure.

60

In testimony whereof I have signed my name to this specification.

WILLIAM THOMAS BUCKINGHAM ROBERTS.
